UNITED STATES PATENT OFFICE.

CHARLES H. REED AND WILLIAM J. VON BUCHWALD, OF PHILADELPHIA, PENNSYLVANIA.

FLAGSTAFF.

1,320,412.

Specification of Letters Patent.

Patented Nov. 4, 1919.

Application filed May 23, 1918. Serial No. 236,127.

To all whom it may concern:

Be it known that we, CHARLES H. REED and WILLIAM J. VON BUCHWALD, both citizens of the United States, residing at 5 Philadelphia, in the county of Philadelphia and State of Pennsylvania, have invented certain new and useful Improvements in Flagstaffs, of which the following is a specification.

10 This invention relates to flagstaffs, more particularly to the rods used for holding railway signal flags or the like, and including the devices designed for the purpose of securing the flag removably to the 15 staff.

This invention consists in the production of parts having special construction and arrangement with respect to each other whereby it is believed the flag may be 20 quickly and conveniently secured or removed, and by which the edge portion of the flag is held strongly against displacement when in service, either by the action of the wind, or by reason of the waving 25 of the flag to and fro by the gateman at a railway crossing or similar situation.

The construction and arrangement of the parts and devices comprising this invention are illustrated in the accompanying drawings, of which Figure 1 represents a longitudinal section of portions of a metal tubular staff with the remaining parts in position thereon. Fig. 2 is a cross-section on the broken line 2—2 of Fig. 1. 35 In this view the scale of drawing is full size. Fig. 3 is an exterior side view of the end of the staff illustrated in Fig. 1, shown full size, and representing the finger latch released. Fig. 4 is an end view, full size, 40 of the right hand end of this invention as shown in Fig. 1. Fig. 5 is a side view of the clamping bar by itself, introduced to illustrate the bowed construction thereof. Fig. 6 is a longitudinal section of this invention illustrating a wooden staff with the remaining parts in position thereon, and in Fig. 6 and the remaining figures of the drawing there is illustrated modified means for securing the pivoted end of the clamping bar in the longitudinal slot of the staff. Fig. 7 is a bottom plan view of the end 50 of this invention as illustrated in Fig. 6 including the means for pivotally connecting the clamping bar to the staff and in the slot thereof. Fig. 8 is a longitudinal sec-

tion of a portion of the wooden staff illustrated in Fig. 6 near the end thereof, and shows the manner in which the pivoted end of the clamping bar may be moved out of the slot in the staff without turning the bar 60 into an angle with the staff. Fig. 9 is a cross-section, full size, on the broken line 9—9 of Fig. 7. Fig. 10 is a cross-section, full size, on the broken line 10—10 of Fig. 1.

65

Throughout the drawings and description, the same letter is employed to refer to the same part.

Considering Figs. 1, 2, 3, 4 and 5, where the staff A is shown it is a piece of metal 70 tubing of suitable size, provided with a longitudinal slot a. A clamping bar B, which has a T-shaped cross-section formed by the curving double flange b, is secured by a pivot pin C to a block D within the 75 tube A and in a slot d of the block. The body of the bar B passes into the slot a of the tubular staff, and the curved flange b lies contiguous to the outer surface of the staff, with the curvature of which it usually 80 corresponds as best shown in Figs. 2, 4, and 10.

To hold the bar in the slot, and in order that it may be conveniently released at will, one end E of the bar B is carried slightly 85 beyond the end or head F of the tube A, and that head is provided with a projecting notched catch f which engages a recessed finger latch e. The forms of the catch f and the latch e are best shown in Figs. 3 90 and 4.

When the flag G is to be secured, the edge portion thereof is folded over the bar B, as shown in Fig. 10, and a portion lies between the flange b and the staff and is 95 clamped against the staff. To insure the contact between the staff and the flange B of the bar throughout the length of the bar, the same is longitudinally bowed slightly as illustrated in Fig. 5. When the 100 bar bearing the edge of the flag is pressed into the slot a and the latch e and catch f engaged, the bar and flange straighten out and flange b clamps the edge of the flag to the staff throughout its entire length 105 making a particularly secure attachment, but enabling the flag to be easily and quickly released.

Now, consider Figs. 6, 7, 8 and 9. The construction is substantially the same as 110

that previously described, but the staff H is of wood. It has a longitudinal slot h within which the clamping bar J, having the flange j, is located. The free end of 5 the bar K extends slightly beyond the end cap k that covers the end of the staff, and the pivot L secures the finger latch M to the end of the bar. The catch for the finger latch is marked m and it projects as shown 10 from the end cap k.

Covering the pivoted end of the bar J, the staff H is provided with an external sleeve N, that has a slot n extending lengthwise and forming a continuation of the slot 15 h in the staff. The end of the bar is pivotally held by means of a flat link O which has a longitudinal slot P engaging a transverse pivot pin Q. Thus, the flat link may move a little back and forth in the direction 20 of the length of the staff in addition to its pivotal movement. The flat link is connected pivotally with the end of the bar J by the pin R.

It will be observed that the bar J has, 25 near the pivot R, a transverse pin r that projects on both sides of the bar as best shown in Fig. 9. When the bar J is clamped in the slot of the staff, the transverse pin r occupies the position shown in broken lines 30 in Fig. 7. Suppose that the finger latch M is now released. It may be turned into the same relative position as the latch e in Fig. 3. Now, the bar J and the attached flat link O can be moved to the left until the pin r 35 is opposite the transverse slot S in the sleeve N. It is believed to be clear that the pin will pass outwardly through the slot S, and the bar may be swung outwardly upon the link O into the position shown in 40 Fig. 8, wherein the bar is parallel with but at a distance without the staff and the flag may readily be inserted or removed.

In the operation of this invention as set forth in Figs. 1, 2, 3, 4, and 5, the edge of 45 the flag is passed over the bar sufficiently to enable a portion of the edge to be clamped by the flange b, as illustrated in Fig. 10, when the latch e and the catch f are engaged.

50 In the operation of this invention as set forth in Figs. 6, 7, 8, and 9, the bar J need not be swung out at a wide angle with the staff. It may be moved into the position shown in Fig. 8, and the edge portion of the flag inserted between the bar and the staff. Now, the bar is moved to the right until the transverse pin r is opposite the transverse slot S, and the pin is passed into that slot 55 and the movement to the right continued. 60 It will here be seen that the pin r is then within the sleeve N and the pivotal end of the bar is thereby held against any displacement outwardly. The finger latch M secures the free end of the bar as already 65 made plain.

Having now described this invention and explained the mode of its operation, what we claim is:—

1. In a flagstaff, the combination with a staff, of a clamping bar, one end of the said bar being freely movable, releasable means for securing the said movable end of the bar to the end of the staff, means for pivotally securing the other end of the bar to the staff, and for permitting a limited longitudinal movement of the said bar in the direction of the said releasable end-securing means, and devices located adjacent to the pivoted end of the bar and brought into engagement by the said longitudinal movement of the bar for holding the pivoted end of the bar closely to the staff. 75

2. In a flagstaff, the combination with a staff, of a clamping bar, one end of the said bar being freely movable, releasable means 80 for securing the said movable end of the bar to the end of the staff, means for pivotally securing the other end of the bar to the staff and for permitting a limited longitudinal movement of the bar in the direction of the said releasable end-securing means, and devices located adjacent to the pivoted end of the bar and comprising a slotted member carried by the staff and a projecting member carried by the bar, the said members being brought into engagement by the longitudinal movement of the bar for holding the pivoted end of the bar closely to the staff. 90

3. In a flagstaff, the combination with a staff, of a clamping bar, releasable means for securing one end of the bar to the end of the staff, a longitudinally slotted sleeve inclosing a portion of the staff and having a transverse slot opening into the longitudinal slot, the said staff having a cavity 100 opening into the slots of the sleeve, means for pivotally securing the said bar to the staff comprising a link mounted in the said cavity of the staff and having a lengthwise movement and a pivotal movement through the longitudinal slot of the sleeve, the said link being pivotally connected with the end of the bar, and the said bar having a transverse pin arranged to pass through 105 the said transverse slot of the sleeve and to engage the interior of the sleeve by a forward movement of the bar. 110

4. In a flagstaff, the combination with a staff, of a clamping bar, releasable means 120 for securing one end of the bar to the end of the staff, means for pivotally connecting the other end of the said bar to the staff, the said means including a device permitting the lengthwise movement of the bar 125 against the staff, a transverse pin projecting from the bar, and means for engaging the pin when the bar is moved lengthwise in one direction whereby the pivoted end of the bar is held contiguous to the staff. 130

5. In a flagstaff, the combination with a longitudinally slotted staff, of a clamping bar constructed to enter the slot of the staff, releasable means for securing one end of the
5 bar to the end of the staff, means for pivotally connecting the other end of the bar to the staff in the slot thereof, the said second means including a device permitting the lengthwise movement of the bar in the said slot, a transverse pin projecting from the bar, and means for engaging the pin when the bar is moved lengthwise in one direction whereby the pivoted end of the bar is held in the slot.
- 10 6. In a flagstaff, the combination with a staff having a longitudinal slot, of a clamping bar having a rib extending lengthwise and side flanges extending from the lower

edge of the rib of the bar and on both sides thereof, the said rib of the bar being longer 20 than the flanges and projecting beyond the ends thereof, one projecting end of said rib being pivotally secured in the slot of the staff and the other projecting end of the rib passing out of the slot at the end of the 25 staff and provided with a pivoted latch, means projecting from the end of the staff for engaging the said latch, the said clamping bar being bowed in the direction of its length to insure contact between the flanges 30 of the bar and the staff when the bar is closed against the staff.

In testimony whereof we affix our signatures.

CHARLES H. REED.

WILLIAM J. VON BUCHWALD.
